UNITED STATES PATENT OFFICE.

ARTHUR W. WARWICK, OF COLORADO SPRINGS, COLORADO, ASSIGNOR TO ARCHIBALD C. SHENSTONE, OF NEW YORK, N. Y.; JOSEPH N. SHENSTONE AND EVA M. SHENSTONE EXECUTORS OF SAID ARCHIBALD C. SHENSTONE, DECEASED.

ORE-AGITATOR.

1,054,629.

Specification of Letters Patent. Patented Feb. 25, 1913.

Application filed November 10, 1911. Serial No. 659,494.

To all whom it may concern:

Be it known that I, ARTHUR W. WARWICK, a citizen of the United States, residing in Colorado Springs, in the county of 5 El Paso and State of Colorado, have invented certain new and useful Improvements in Ore-Agitators, of which the following is a specification.

This invention relates to an agitating 10 tank for agitating and intimately mixing finely crushed ore particles with a solution of a chemical or chemicals, and has for its object to provide an apparatus wherein such agitation and intimate mixture are performed efficiently and rapidly, and the 15 chemical reaction between the ore particles and the active solvent is thereby hastened.

The invention consists in the provision in such agitating tank of a lift pipe which is 20 closed at the top and open at the bottom and which has lateral perforations arranged below the level of the material being agitated, and in the provision of means whereby the said solution and the finely 25 crushed ore (which together are hereinafter called the pulp) are caused to circulate upwardly through the said lift pipe through the perforations in which they are projected radially and settle.

30 The invention also consists in the provision of auxiliary air injectors arranged below said lateral openings which aid in hastening the said chemical reactions.

These and other objects, which will be 35 hereinafter referred to, are fully described in the following description.

The drawings accompanying this application illustrate a desirable and practical apparatus embodying the said invention.

40 In the said drawings,—Figure 1 illustrates a vertical section of the agitating tank and connections. Fig. 2 is a plan view thereof. Fig. 3 is a detail section of the upper part of the lifting pipe. Fig. 4 is a 45 detail view of one of the auxiliary air injectors. Fig. 5 is a view similar to Fig. 1, illustrating a modified form. Fig. 6 is a similar view, illustrating another modified form.

50 In carrying my invention into practice an agitating tank which may be of any desired form is fitted with a lift pipe which is capped at the top and open at the bottom, and has lateral perforations. The

top is located below the level of the material being agitated and means are provided for forcing such material upwardly through the lift pipe whence it projects outwardly through the said openings in a radial direction. Various means may be employed for this 55 purpose. An air lift may be employed or a screw propeller located in the pipe, or the pulp may be taken from the top and pumped up through the said lift pipe. In connection therewith I preferably employ auxiliary air jets which are located near the lowest, part of the tank, and preferably above the bottom of the lift pipe, and which very readily keep the pulp or very finely divided and light part thereof in suspension. The 60 heavy, coarse or gritty particles of the pulp subside rapidly to the bottom of the lift pipe there to be picked up by the air jet or pulp jet or sucked up by the propeller. The material thus lifted is forced out of the lift 65 pipe radially across the tank to fall through the pulp in an irregular and possibly zig-zag manner against the air bubbles set free by the auxiliary air jets. Where the air is employed as the lifting medium in the lift 70 pipe it ascends upwardly from the lateral perforations therein in a curved direction, and assists in agitating the more finely divided particles which are held in the upper 75 levels of the material being agitated. By 80 means of the foregoing it will be seen that in a comparatively short period of time every particle of solid material will have been passed through a fresh volume of solution, thus particularly hastening the chemical 85 action of the solution upon the solid material.

The particular apparatus employed by me to carry my invention into effect comprises a tank A which may be of any suitable form 90 or construction and may very well take the form illustrated in Fig. 1, wherein a cylindrical body a is joined to a conical base a', which may be supported in any suitable manner, as for instance upon the foot a². 95 Within the said tank and preferably centrally disposed therein, as illustrated, is the lift pipe B which is open at the bottom for the admission of pulp from the tank and is supported in any suitable manner, as for instance upon feet b which rest upon ledges in the foot a². 100 The upper end of this lift pipe is closed, preferably by a cap b', and

upon the side thereof near the top are perforations b^2 which are illustrated as extending in two annular rows about the said lift pipe. The said perforations are preferably disposed close to the top of the lift pipe and are located well below the level X of the pulp in the tank A. In the particular instance illustrated such perforations are substantially two-thirds of the height of the said tank. Means are provided for holding the said lift pipe in position comprising braces b^3 attached thereto and to the tank, as indicated in Fig. 3.

Means are provided for causing an upward circulation of the pulp in the lift pipe B and in the form illustrated in Fig. 1 such means comprise an air injector C which is located at the bottom of the said lift pipe and is arranged to inject a current of air upwardly therein. This is supplied with air through pipe e which may transmit air under pressure from any suitable source, as for instance a centrifugal fan or blower c'.

The air passes upwardly through the lift pipe drawing in pulp at the bottom thereof and causing an upward circulation of the pulp therein, and both air and pulp emerge through the perforations b^2 where they are projected laterally. The air then takes an upward course as indicated by arrows, Fig. 1, and assists in agitating the finely divided pulp above, while the heavier ore particles settle through the pulp toward the conical base and an active and efficient agitation of the pulp is thereby realized.

To assist the agitation, I preferably provide auxiliary air injectors D. As illustrated, the said air injectors are located upon an air pipe d which is connected by outside connections d' to the compressed air pipe e. Any suitable number of such air injectors D may be employed, depending upon the capacity of the apparatus. They are preferably located in about the position shown in Fig. 1, wherein they are adjacent the conical bottom a' and project downward. The outlet of the said auxiliary air injectors is preferably covered by a screen d^2 which may be made of suitable textile or fibrous material not too close in texture. Canvas bags made of No. 8 canvas have heretofore been found suitable for this purpose.

The dimensions which the said apparatus will assume are subject to variation, depending upon the particular uses or needs of the engineer. I have found that a tank constructed to agitate 100 tons of finely pressed ore and 200 tons of solution for example may be made 18 feet in diameter in the cylindrical portion, and 10 to 15 feet from the bottom of the cylindrical portion of the said tank to the apex of the conical bottom. The lift pipe in such case may have a diameter of about 10 inches, and the perforations may be in two rows as shown,

16 in each row. The perforations are about two inches in diameter. The employment of six auxiliary jets will satisfactorily perform the function assigned to them. These jets may well be made of one inch iron nipples which may be suitably secured in the ring d, as for instance by being screwed therein. The pipe d would have a proper dimension if constructed of two and one-half inch pipe.

In Fig. 5 I have illustrated an apparatus constructed according to my invention, wherein the overflow of pulp is caught at the top in a funnel E, whence it is conveyed by pipe e to a centrifugal pump F and thence through pipe f to the injector C. In this form the agitation of the pulp is accomplished by pumping the overflow of the pulp directly upward through the lift pipe B, whence it passes outwardly through the perforations b^2 and thoroughly agitates the mass. Air under pressure is supplied through the auxiliary air jets D, as before described, and acts to agitate the pulp and to cause descending heavy or gritty particles which are passed out through the perforations in the lift pipe to meet fresh particles of solution and thereby hastening the chemical reaction.

In Fig. 6 I have illustrated the employment of other means for producing the circulation through the lift pipe B. Here a screw propeller G is employed for this purpose. This is located at a convenient portion of the said lift pipe. As shown, it is substantially half way up. This propeller is supported upon a shaft g and is turned from pulley g' . It passes through a perforation in the cap b' and passes through a stuffing box g^2 upon the said cap and is supported thereon by a disk g^3 secured to the said shaft. In this form the auxiliary air jets are not illustrated, and my invention is not necessarily limited to the employment thereof, although I have found them very advantageous, nor is my invention limited to the particular manner of effecting the circulation through the lift pipe.

Although in Fig. 6 I have illustrated the screw propeller as being operated by a shaft from above, the location of this shaft is not a matter of moment, and it can as well be introduced otherwise than as shown. Nor is it to be inferred from the particularity with which I have described detailed features of construction that my invention is necessarily limited thereto, as equivalent devices may be employed within the limits of the appended claims without departing therefrom.

What I claim is:—

1. An agitating tank having a lift pipe the top of which is below the normal level of the material being agitated and which is closed at the top and open at the bottom and

has lateral openings, and means for causing a circulation through said pipe.

2. An agitating tank having a lift pipe closed at the top and open at the bottom and having lateral openings formed in said lift pipe below the normal level of the material being agitated, and means for causing a circulation through said pipe.

3. An agitating tank having a lift pipe closed at the top and open at the bottom and having lateral openings formed in said lift pipe which are below the normal level of the material being agitated, means for causing a circulation through said pipe, a series of auxiliary injectors arranged below said lateral openings and adapted to agitate the material below such openings, and means for injecting agitating material therethrough.

4. An agitating tank having a lift pipe closed at the top and open at the bottom and having lateral openings formed in said lift pipe which are below the normal level of the material being agitated, means for causing a circulation through said pipe, a series of auxiliary injectors arranged below said lateral openings and adapted to agitate the material below such openings, screens for said injectors, and means for injecting agitating material therethrough.

5. An agitating tank having a lift pipe, the upper end of which is below the normal

level of the material being agitated, and which is closed on top and open at the bottom and is provided with lateral openings near the top, the lower end of said lift pipe extending adjacent to the bottom of said tank, and means for causing a circulation through said pipe.

6. An agitating tank comprising an annular casing provided with a conical bottom, a substantially centrally located lift pipe having its upper end below the normal level of the material being agitated, said lift pipe closed at the upper end and open at the bottom which is adjacent the apex of said cone and having lateral openings near the top, an upwardly projecting air injector located within the lower end of the pipe, downwardly projecting auxiliary air injectors located near the bottom of said tank and means for injecting air into said upwardly projecting injector and into said auxiliary injectors, and fabric screens for said downwardly projecting injectors.

In witness whereof, I have hereunto signed my name in the presence of two subscribing witnesses.

ARTHUR W. WARWICK.
